UNITED STATES PATENT OFFICE.

WILLIAM H. E. HOOPER, OF DETROIT, MICHIGAN.

BASEBALL GAME BOARD.

Application filed May 24, 1921. Serial No. 472,138.

To all whom it may concern:

Be it known that I, WILLIAM H. E. HOOPER, a citizen of the United States, residing at Detroit, in the county of Wayne and State of Michigan, have invented certain new and useful Improvements in Baseball Game Boards, of which the following is a specification.

This invention relates to games and toys, 10 and pertains especially to baseball game devices for playing the game on a board having the diamond and field depicted thereon according to the rules and regulations of professional baseball.

15 The object of the invention is to provide certain novel and peculiar indicia in the fields and diamond as represented on a board for showing the status of players "at bat" and to furnish devices such as a plurality of darts for each player to hurl or throw against the board in playing a baseball game, so as to denote the field player making "an out".

20 A further object of the invention is to provide, in a baseball playing board, relative arrangement of sections or location of devices on the face of the board which shall indicate the "outs" in center, left and right fields, respectively, when such devices 25 are struck by an arrow or dart hurled or thrown by players of a team "at bat", and to furnish the bases, home plate and catcher's position, as well as the pitcher's position and diamond field with similar devices indicating "outs" and "home runs" when struck 30 by the arrows or darts, and also to furnish the face of said board with data indicating "base hits" within fair territory when the darts strike such territory.

35 40 In the accompanying drawings forming part of this application:—

Fig. 1 is a plan view of the board, showing its various indicia for playing a baseball game.

45 Fig. 2 is a detail perspective view of part of the board showing a dart as having been thrown by a player.

The same reference characters denote the same parts throughout the several views of 50 the drawings.

In carrying out my invention, I prefer- 55 ably employ a body or main board member of back 5 of such material and thickness as will afford stiffness and rigidity for stand- 60 ing or hanging the board in playing posi- 65 tion. I further employ a face board mem-

ber 6 glued or otherwise secured to and covering one side of the main board member 5. The board member 6 may be composed of fibre or cork in one or more layers so as 60 to form a cushion or penetrating surface for the playing arrows or darts as 7. The outer face of said surface being such as to permit the playing diagram to be depicted thereon, or to be printed on sheets which may be 65 pasted thereon, so that in the event of a sheet becoming disfigured or impaired by repeated punctures in throwing the darts, new sheets may be supplied, but the field diagram may be otherwise produced on the 70 dart-receiving face, as by permanently producing the diagram on the cushion member in the manufacture thereof.

The playing face of the board comprises two contrasting colors, as green for the field 75 and white, or some color clearly contrasting with the field color, for the bases, base lines, foul lines, pitcher's box, "outs" for center, left and right fields, as well as to 80 infield indicia.

In illustrating the diagram, no attempt is made to show the diagram or fields in colors, it being understood that any desired colors or simply black and white may be used. The dart has a representation of a 85 regulation base ball as 7a.

The left, center and right fields are provided, respectively, with circular planes or disks as A. B. C., all of which are of the same color but contrasting with the colors 90 of said fields. Said circular planes contain the names of the said fields and the word "Out," so that a player throwing a dart within either of the circles A. B. C., shall 95 be declared out. The left and right fields have the indicia "count 1" appearing thereon adjacent to the "out" circles of these fields, so that a player throwing a dart upon 100 the outer gardens or fields shall be given credit for a "single" or one base hit, and 100 count one.

The home plate has a circular plane D of the same color as the outer field circles, and depicted on the circle D are the words and numeral "Home run, count 3," so that a 105 player throwing a dart into the circle D shall be credited with a home run and count three. Each of the bases have circles of the same color as the aforesaid circles, and said base circles as E. F. G., respectively, 110 have the indicia "First base out," so that a player throwing a dart into any one of the

base circles shall be declared out. The catcher's box is represented by a rectangle or square H of the same color as the base circles, and the words "Catcher out" appears thereon, so that a player is out when he throws a dart into the catcher's box. The pitcher's box K is of the same color as the base circles and has the words "Pitcher out" thereon, so that a player is out when he throws a dart into the pitcher's box. A small disc or circle L is placed on the in-field or diamond, having the words "Short stop out," and is of the same color as the other circles, so that a player is out when he throws a dart into this circle. A similar disc or circle M, of the same color as the other circles, is made in the infield on the opposite side of the pitcher's box from that of the short stop circle, and this circle has the words and number "Home run 3" thereon, indicating that a player who throws a dart into this circle shall be credited with a home run. The infield or diamond has the word and numeral "Count 2" thereon, so that a player throwing a dart into the infield not occupied by the pitcher's box and small circles L and M shall be credited with a two-base hit and count 2. The foul territory is indicated by the words "Foul ball."

Obviously the base and field players, that is the "in and outfields," pitcher and catcher may be given credit for their respective "put outs" when a dart lodges in its position as indicated by the discs or circles and the boxes of the pitcher and catcher.

The game is played similar to the regular and actual baseball game by two or more, or by the usual number of players for each team taking their turns of "at bat" and "field," each player at bat standing about ten feet from the board and being provided with three darts giving each player an equal number of chances or throws for "getting on" or "getting out" by anchoring the dart upon the board in such position as would indicate whether he is "safe" or "out," or the number of bases he is entitled to by reason of his allotted dart throws, and if "out" the player making the out will be indicated by the position of the dart. Foul

balls when caught, the batters are out, when not caught, the batter making three fouls in succession is out.

Obviously, the rivalry and skill of the players is tested in throwing the darts so as to avoid the various "outs," and to have the dart stick or anchor in the "counts."

I do not wish to be understood as confining myself to any particular size of the board or colors, nor to the size and location of the outfield discs or circles and the two infield circles, but reserve the right to make such changes and variations therein and in the manufacture of the invention as may be consistent with the appended claims.

Having thus described my invention what I claim as new and desire to secure by Letters Patent is:—

1. A base-ball game device, comprising a playing board representing a base-ball diamond and in-field and out-field each marked with a scoring value for the player, other areas indicating the usual positions occupied by the members of the opposing team and marked with values adversely affecting the score of the player, a home plate and an area of the in-field each of the two last-named areas being in juxtaposition with an area of adverse value and each marked with a maximum scoring value for the player.

2. A base-ball game device, comprising a playing board representing a base-ball diamond and in-field and out-field each marked with a scoring value for the player, other areas indicating the usual positions occupied by the members of the opposing team and marked with values adversely affecting the score of the player, areas along the base lines connecting the positions of the basemen and of similar scoring value, and a home plate and an area of the in-field each of the two last-named areas being in juxtaposition with an area of adverse value and each marked with a maximum scoring value for the player.

In testimony whereof I affix my signature in presence of two witnesses.

WILLIAM H. E. HOOPER.
